UNITED STATES PATENT OFFICE

137,793

DESIGN FOR A PLATE OR SIMILAR ARTICLE

Alfred Duhrssen, New York, N. Y.

Application January 15, 1944, Serial No. 112,245

Term of patent 3½ years

(Cl. D44—15)

To all whom it may concern:

Be it known that I, Alfred Duhrssen, a citizen of the United States and a resident of the city of New York, Borough of Manhattan, in the county and State of New York, have invented a new, original, and ornamental Design for a Plate or Similar Article, of which the following is a specification, reference being had to the accompanying drawing, forming part thereof.

Figure 1 is a fragmentary face view of a plate showing my new design, the right end thereof being shown broken away in order to avoid con-

tact with the margin. A repeat unit of the design is contained between the dotted line segment at the top of the plate. Said unit is repeated about the circumference of the plate in the relation indicated by the extension of the detailed showing beyond the dotted lines.

Figure 2 is a side elevational view of the plate, on a reduced scale.

I claim:

The ornamental design for a plate or similar article, substantially as shown and described.

ALFRED DUHRSSEN.
